(57) **CLAIM**

We claim the ornamental design for box for feeding animals, as shown and described.

DESCRIPTION

FIG. 1 is a front perspective view of a first embodiment of a box for feeding animals showing our new design.

FIG. 2 is a front view thereof.

FIG. 3 is a back view thereof.

FIG. 4 is a right side view thereof.

FIG. 5 is a left side view thereof.

FIG. 6 is a top view thereof.

FIG. 7 is a bottom view thereof.

FIG. 8 is a front view of a second embodiment of a box for feeding animals showing our new design, with the back side, right side, left side, top and bottom views being identical to FIGS. 3-7, respectively.

FIG. 9 is a front view of a third embodiment of a box for feeding animals showing our new design, with the back side, right side, left side, top and bottom views being identical to FIGS. 3-7, respectively.

FIG. 10 is a front view of a fourth embodiment of a box for feeding animals showing our new design, with the back side, right side, left side, top and bottom views being identical to FIGS. 3-7, respectively.

FIG. 11 is a front perspective view of a fifth embodiment of a box for feeding animals showing our new design.

FIG. 12 is a front view thereof.

FIG. 13 is a back view thereof.

FIG. 14 is a right side view thereof.

FIG. 15 is a left side view thereof

FIG. 16 is a top view thereof; and,

FIG. 17 is a bottom view thereof.

It is understood that portions of the carton shown in long broken lines (— — —) represent perforations, which form part of the claimed design. It is further understood that short broken lines (---) or shading shown in the figures are for illustrative purposes only and form no part of the claimed design. It is also understood that the following pattern (— - - - - - - - -) represent perforations, which form no part of the claimed design.
